UNITED STATES PATENT OFFICE

ALFRED PETERSON, OF DENVER, COLORADO

APPARATUS FOR GLUING BACKS ON TO BOOKS

Application filed January 27, 1928. Serial No. 249,897.

This invention relates to a method of gluing backs on to books and to a machine for performing said method and has for an object to provide a rapid, efficient, simple and economical method and machine of the class described.

Machines have been devised and are in use for gluing backs on to catalogs, paper covered directories and other books but such machines 10 are so large, complicated and expensive as to preclude their use in small plants, whether in large or small communities, in which jobs requiring such work are infrequent and it is the object of the present invention to provide 15 both a new and improved, simple and efficient method of gluing backs on to books and a machine for that purpose which shall be so small, simple and cheap that the profits from one or two ordinary catalog or similar jobs 20 will pay for the installation of the machine so that almost any small print shop can afford to have such a machine as a part of its equipment.

Because of the efficiency of the method and 25 machine hereinafter described and claimed, the use thereof will not, however, be by any means limited to such small shops.

The foregoing and other objects will more 30 fully appear from the following specification and claim as illustrated in the accompanying drawings wherein like characters of reference indicate corresponding parts throughout and in which.

Figure I is a plan of the machine, a portion 35 of the top being broken away and certain parts being shown in section and other parts in dotted lines.

Figure II is a section on line A—A of Fig. 40 I, looking in the direction of its arrow.

Figure III is a section on line B—B of Fig. I, looking in the direction of its arrow.

Figure IV is a section on line C—C of Fig. I, looking in the direction of its arrow.

Figure V is a detail view in section of the 45 adjustable gluing wheel assembly.

Figure VI is an illustration of a cover for a book showing the cover creased and the glue applied, both in a preferred manner.

A common method of gluing backs on to 50 books is to place the books in a pile with

their backs in alignment and apply the glue by brush or other suitable means to the plurality of the backs thus aligned, thereafter taking the books one at a time and placing the glued back of the book into the cover at 55 the proper place. The books must be taken from such a pile while the glue is sufficiently moist to properly stick to the back of the book when applied. In this condition the glue is so stringy that when the books are separated 60 the glue will string out and mess the job.

In many cases the cover cannot be held to the book in a sufficiently secure manner by applying the glue simply at the back edge of the book. In such cases it is a common expedient 65 to apply glued strips of cloth or the like to the book and the cover, inside the cover and adjacent the back, and to thus reinforce the binding between the book and the cover. Obviously such an operation is cumbersome and 70 takes a considerable amount of time and expense both for materials and labor.

The present invention eliminates the objections above specified, as well as other objectionable features in the gluing of covers 75 on to books according to present commonly employed methods and also generally simplifies and cheapens the entire operation.

The method constituting a part of the present invention comprises running the 80 cover, while still flat, over a support and applying to the cover a streak of glue of the desired width, passing the cover, in a continuous process, to a carrier arranged to keep the glued portion of the cover from contact 85 with anything else, and delivering the cover from the carrier to a table where the book is to be set in the cover, one of the vital parts of the method being that the speed of movement and the length of the carrier are so arranged and adjusted that, considering the consistency of the glue used, the glue will, during its passage on the carrier while exposed to the air, dry to the proper consistency 90 for immediate insertion of the book in the 95 cover. By this method the operation is made continuous; no glued books or glued covers are permitted or required to be cared for and protected with regard to smearing the glue or contacting with other objects and the 100,

proper consistency of the glue is automatically provided for throughout the running of the job, subject only to the proper regulation, easily determined and accomplished by those skilled in the art, at the beginning of the job.

5 A further feature of the process is the provision for the reinforcement at the sides of the binding to eliminate the use of strips of cloth or other material as above referred to.
10 In operating the method, where such a binding is required, the cover is first creased by any suitable machine or method in common use for such purposes, four creases being made in the cover as clearly illustrated at
15 Fig. VI. The glue is thereafter applied to the cover in a strip, covering all the space between the two outer creases. The back of the book is positioned in the space between the two inner creases, and the sides of the
20 cover are then pressed against the sides of the book whereby the glued strips on either side of the central strip will be attached to the sides of the book adjacent the back. The two inner creases mark the strip for the placing
25 of the back of the book and also provide for the easy and efficient bending of the back of the book at the edges of the back. The two outer creases form hinges for the opening of the sides of the book, these creases being
30 at the edges of the glued strips which attach to the sides of the book adjacent the back thereof. By this method a double reinforced
35 glued back is provided without trouble, work or expense in addition to that required for the simple back-gluing of the cover, except the additional work of creasing the covers. All work and expense incident to the usual operation of placing and gluing the cloth strips as above described is eliminated.
40 For the operation of this method and for the general simplification and cheapening and making more efficient the operation of gluing backs or covers to books, the present invention includes a machine for this purpose
45 which will now be described.

A tank 1 supported on standards 2 is provided for holding water 3 to be heated by any suitable means as burner 4 positioned beneath the tank.

50 A glue pot 5 holding glue 6 is provided to be supported in the water tank in any suitable manner as by hooks 7 engaging the upper edges of partitions 8 in the tank 1. Handles 9 are provided for lifting the glue pot 5 from the tank when desired. By this construction the glue 6 may be kept at the temperature and consistency desired, by means of the partial immersion of the glue pot in the heated water in the tank.

60 A table top 10 with side flanges 11 is provided, having apertures 12 therein to permit rollers 13 to project upwardly therethrough for moving the work across the table top 10 as hereinafter described. The top 10 is also
65 provided with a cut-away 14 extending from

a point back of the gluing wheel, hereinafter described, and continuing thence to the delivery edge of the top adjacent the carrier, as hereinafter described.

A shaft 15 is revolvably mounted in the walls of the tank as at 16 and has mounted thereon rollers 13 projecting through the top 10, as hereinabove described. The rollers 13 are protected from the water 3 by means of suitable semi-circular partitions 17 running from the walls of the tank to the interior partitions 8.

A shaft 18 is mounted above and parallel to the shaft 15, by any suitable means as supports 19, and provided with suitable means as crank 20 for revolving the same, and carries rollers 21 attached to the shaft by screw collars 22 and positioned opposite and for co-action with the rollers 13 and engaging the same whereby the revolution of the shaft 18 will, through the engagement of rollers 21 and 13, cause the shaft 15 to be revolved.

Guide rollers 23 are likewise attached to the shaft 18 by screw collars 24, the screw collars 22 and 24 permitting ready adjustment, longitudinally of the shaft 18 of the rollers 21 and 23.

Slots 25 may be provided for the accommodation of the work positioning slide 26 which is of common construction and well understood by those skilled in the art and requires no further description.

The gluing wheel assembly shown in detail in Fig. V is mounted upon the shaft 15 within the glue pot 5 and consists of a sleeve 27 provided with a flange 28, the shaft 15 and the collar 27 being provided with a series of registering holes 29 to accommodate a pin 30, and the flange 28 and shaft 15 being provided with registering holes for the accommodation of the pin 31.

The gluing wheel is formed of any suitable number of sections 32 adapted for slidable mounting on the collar 27 and for retention thereon by the flange 28 on the one side and the pin 30 on the other side of the section or sections constituting the wheel, it being understood that each of the sections is of a thickness corresponding to the space between the holes 29 whereby any number of sections may be added to the wheel and may be held in substantially compact or solid position as a single wheel on the collar 27 by means of the flange 28 on one side of said sections and a pin 30 inserted through the hole 29 on the opposite side of the wheel thus formed.

Sections of the wheel not desired for use may be slid from the collar and hung upon the shaft 15 in the manner clearly shown at the left of Fig. V where they will idle upon the shaft 15, their tops being a substantial distance below the tops of those sections which are in position upon the collar and which form the gluing wheel.

For ready assembly and disassembly of the

machine it is found convenient to provide the walls of tank 1, the partitions 8 and the walls of the glue pot 5 with notches 33 whereby the shaft 15 may be let down into said notches to its mounting 16 in the walls of the tank 1 and may be readily lifted therefrom. For the same purpose it is found convenient to have the standards 19 bolted to the flanges 11 of the top 10 as at 34, whereby the entire assembly of top 10, shaft 15 and shaft 18 with their associate parts may be readily lifted out of the machine and out of the tank, whereupon the glue pot 5 may also be easily removed from the tank.

15 It will be understood that the glue will be maintained in the glue pot at a sufficient height to engage the lower portion of the gluing wheel composed of sections 32 mounted upon the collar 27 and it will also be understood that the water line in tank 1 will be maintained above the bottom of the glue pot but below the bottom of the notches 33 so as to prevent leakage of water therethrough.

20 25 A carrier of any suitable construction, well understood by those familiar with the art, is provided and on account of such familiarity only a portion thereof has been shown, namely, the roller 35 which may be suitably mounted as by lugs 36 on the tank 1 and provided with grooves 37 for the accommodation of carrier cords 38 which cords, as will be understood, extend to and engage a roller similar to the roller 35 and spaced therefrom at any suitable distance for the purpose of permitting the glue on the carried covers to properly dry during the passage of the cover over the carrier as above referred to and as hereafter more fully described.

40 45 It will be understood also that a space is provided in the carrier between the carrier cords 38 and constituting a continuation of the cut-away 14 in the top 10, this space being provided for the glued strip on the cover during its passage over the carrier, that is to say, that the carrier cords are so positioned as not to contact with the glued strip on the cover while it is being carried by the carrier.

In operation, a cover for a book is placed upon the top 10 and against the slide 26 for proper positioning thereof to bring that portion of the cover which is to form the back of the book in alignment with the gluing wheel, it being understood that the outside of the cover is placed upward so that the glue wheel will apply the glue to the inside of the cover. The cover is slid forward into the jaw formed between the rollers 21 and 13. The handle 20 is revolved causing revolution of shafts 18 and 15 and likewise the revolution of the gluing wheel and the revolution of the rollers 21 and 13 will cause them to engage the edge of the cover and draw the same forward over the gluing wheel which will, in the process, apply the glue to the cover in a strip at the

predetermined portion thereof. The rollers 23 are provided for depressing the central portion of the cover for insuring its engagement with the gluing wheel and the proper application of the glue thereto. The number of sections 32 of the gluing wheel composing the same at the time of the operation will obviously determine the width of the strip which is glued. The sections 32 which do not at the time form a part of the gluing wheel 75 will be out of engagement with the cover by reason of their position on the shaft 15, as clearly shown at Fig. V.

It will be remembered that adjacent and beyond the gluing wheel the top 10 is cut 80 away as at 14 so that after the cover passes the gluing wheel and thence on to the carrier there will be nothing beneath the cover and opposite the glued strip to contact with the cover or the glue thereon, it being understood that the carrier cords 38 are of sufficient thickness to hold the cover above and away from the roller 35.

After the cover passes on to the carrier, it is carried thereby to a table or other suitable place where an operator takes the cover from the carrier and inserts the book therein.

As previously stated, the length of the carrier and the speed thereof are arranged relatively to each other and to the consistency of 95 the glue so that the length of time consumed in the passage of the cover from the gluing wheel to and over the carrier, through the air, will be sufficient and only sufficient to permit the drying of the glue on the cover to the 100 proper point for attachment thereto of the book. This relative adjustment of the length and speed of the carrier and consistency of the glue can be readily determined and made, by those skilled in the art, at the beginning of 105 any given operation, and after such adjustment is made no further skill is required and an unskilled operator may thereafter complete the operation, the gluing and the proper drying of the glue being automatically provided for in the manner hereinabove described.

It will be understood that various changes and modifications in the construction and arrangement of parts of the machine may be 115 made within the spirit and scope of this specification and the appended claim.

The cheapness and simplicity, as well as the efficiency of the machine will be apparent from the foregoing description, to those 120 familiar with the art.

It will be obvious that the roller 35 may be cut away at a point opposite cut-away 14 so as to avoid contact of the roller 35 with the glued strip in case the cords 38 are so small 125 in diameter as not to stand out above their grooves 37.

I claim:

In a machine for applying adhesive material to sheets, a shaft, a hub carried by and of 130

greater diameter than the shaft and a gluing wheel, comprising sections adapted to be relatively attached to form a wheel on said hub, of different widths predetermined according to the number of sections thus attached, said sections being relatively detachable and adapted to be removed from said hub and to hang upon said shaft and out of operative position when detached.

10 In testimony whereof, I affix my signature.
ALFRED PETERSON.
